(57) **CLAIM**

The ornamental design for a display screen with icon, as shown and described.

DESCRIPTION

FIG. 1 is a front view of an icon on a display screen, showing our design.

FIG. 2 is an enlarged view of the icon in FIG. 1; and, FIG. 3 is another view of the icon in FIG. 1 showing the icon on a display screen of a watch.

The dash-dash broken line rectangle with rounded corners illustrates a display screen and forms no part of the claimed design. The remaining dash-dash broken lines in FIG. 3 illustrate a watch that form no part of the claimed design. The dot-dash broken line circle and the dot-dash lead line in FIG. 1 that is labelled FIG. 2 indicates the area from which the enlargement in FIG. 2 is taken and forms no part of the claimed design.
